US00D611569S

(12) **United States Design Patent**
Born et al.

(10) **Patent No.:** US D611,569 S
(45) **Date of Patent:** ** Mar. 9, 2010

(54) **DISPENSER CARTRIDGE**

(75) Inventors: **Jason Alan Born**, Loveland, OH (US); **David James Emmons**, Plymouth, MN (US); **Johannes Nikolai Gaston**, Minnetonka, MN (US); **Douglas James VanOrnum**, Minnetonka, MN (US); **Dominic James Daunter**, Howell, MI (US); **Noah Eberhard Dingler**, Waterford, MI (US)

FOREIGN PATENT DOCUMENTS

(73) Assignee: **PUR Water Purification Products, Inc.**, Cincinnati, OH (US)

DE 296 11 611 U1 3/1996

(**) Term: **14 Years**

(Continued)

(21) Appl. No.: **29/333,732**

Primary Examiner—Robin V Webster

(22) Filed: **Mar. 13, 2009**

(74) Attorney, Agent, or Firm—Cynthia L. Clay; Kelly L. McDow; Andrew A. Paul

Related U.S. Application Data

(62) Division of application No. 29/318,924, filed on May 30, 2008, now Pat. No. Des. 591,389, which is a division of application No. 29/250,520, filed on Nov. 17, 2006, now Pat. No. Des. 592,729.

(57) **CLAIM**

The ornamental design for a dispenser cartridge, as shown and described.

(51) **LOC (9) Cl.** 23-01
(52) **U.S. Cl.** D23/209

DESCRIPTION

(58) **Field of Classification Search** D23/207, D23/209; D3/202; 210/85, 198.1, 436-437; 222/189.06

See application file for complete search history.
